(57) **CLAIM**

I claim the ornamental design for an easel, as shown and described.

DESCRIPTION

FIG. 1 is a front perspective view of a third preferred easel shown in a folded closed configuration.

FIG. 2 is a back perspective of the easel of FIG. 1.

FIG. 3 is a top view of the easel of FIG. 1.

FIG. 4 is a bottom view of the easel of FIG. 1.

FIG. 5 is a front view of the easel of FIG. 1.

FIG. 6 is a back view of the easel of FIG. 1.

FIG. 7 is a first side view of the easel of FIG. 1.

FIG. 8 is a second side view of the easel of FIG. 1.

FIG. 9 is a front perspective view of the third preferred easel in a first open configuration with the painting compartment substantially parallel to the palette compartment.

FIG. 10 is a back perspective of the easel of FIG. 9.

FIG. 11 is a top view of the easel of FIG. 9.

FIG. 12 is a bottom view of the easel of FIG. 9.

FIG. 13 is a front view of the easel of FIG. 9.

FIG. 14 is a back view of the easel of FIG. 9.

FIG. 15 is a first side view of the easel of FIG. 9.

FIG. 16 is a second side view of the easel of FIG. 9.

FIG. 17 is a front perspective view of the third preferred easel in a second open configuration with an inner cover of the palette compartment open.

FIG. 18 is a back perspective of the easel of FIG. 17.

FIG. 19 is a top view of the easel of FIG. 17.

FIG. 20 is a bottom view of the easel of FIG. 17.

FIG. 21 is a front view of the easel of FIG. 17.

FIG. 22 is a back view of the easel of FIG. 17.

FIG. 23 is a first side view of the easel of FIG. 17.

FIG. 24 is a second side view of the easel of FIG. 17.

FIG. 25 is a front perspective view of the third preferred easel in a third open configuration with an inner cover of the palette compartment wrapped over the back of the palette compartment.

FIG. 26 is a back perspective of the easel of FIG. 25.

FIG. 27 is a top view of the easel of FIG. 25.

FIG. 28 is a bottom view of the easel of FIG. 25.

FIG. 29 is a front view of the easel of FIG. 25.

FIG. 30 is a back view of the easel of FIG. 25.

FIG. 31 is a first side view of the easel of FIG. 25; and,

FIG. 32 is a second side view of the easel of FIG. 25.

The easel is shown with symbolic breaks in its length and width. These symbols indicate that any portion of the article beyond what is shown forms no part of the claim.

1 Claim, 22 Drawing Sheets
